CLAMP

Cloyes R. Carson, Santa Clara, Calif.

Application August 30, 1939, Serial No. 292,651

2 Claims. (Cl. 248—226)

The present invention relates particularly to a form of clamp adapted to adjustably support a mechanism on a hospital bed.

In the application of various means for treatment of bedridden patients in hospitals it has been common practice to use a movable floor stand upon which such means, such as irrigators, croup tents, etc., are suspended. Such stands are highly objectionable for many reasons. For instance, they are quite heavy; they are without wheels because they must maintain a rigid position when once placed, and consequently they must be dragged from one bed to another, or from one room to another; standing upon the floor, they seriously obstruct the operations of the attendant nurse and doctors; they are clumsy, unwieldy, and inefficient.

It is therefore, one object of the present invention to provide a means for properly supporting a device or devices of any kind over a hospital bed without in any manner obstructing the floor area about the bed, and that will effectively correct the objectionable features above set forth.

It is also an object of the invention to provide means of the character indicated that can be easily attached to, or removed from, the side rail of a bed; that will permit the quick and easy adjustment of the devices supported thereon relative to the bed; that will be economical to manufacture, light in weight, quickly and easily assembled and disassembled, strong, durable, and highly efficient in its practical application.

In the drawing:

Figure 1 is an isometric perspective view showing a device embodying my invention, partly in section and with part broken away.

Figure 2 is a side elevation of the same showing the mode of application to a bed rail.

Figure 3 is a horizontal sectional view of a modified form.

Referring now more particularly to the drawing, I show at 1 a rectangular housing, the top of the same being indicated at 2, the bottom at 3, the two sides at 4 and 5, and the outer end at 6.

The top 2 is projected beyond the sides 4—5 as at 7, and terminates in a downwardly and inwardly turned flange forming a hook as 8.

The bottom 3 also is projected beyond the sides 4—5 as at 9 and terminates in an upwardly turned flange as at 10.

In the present case the bed rail is shown at 11 as an angle iron with one flange lying in a horizontal plane and the other in a vertical plane,

and directed inwardly and downwardly, respectively, as at 12 and 13.

Since the hook 8 and flange 10 perform active services in securing the clamp in position it is desirable that they be proportioned so as to engage the flanges 12—13 with the least possible movement. To this end the distance 14 is made a little greater than the width of flange 12, and the distance 15 is just great enough to permit the flange 13 to seat in the shoulder between the part 9 and the adjacent edges of sides 4—5 and permit the hook 8 to pass over the edge of flange 12.

By means of the above arrangement and proportioning of the several parts to place the clamp 15 on the rail it is only necessary to first seat the bottom edge of flange 13 as above described, and as shown clearly in Figure 2, then swing the housing 1 into a horizontal position and seat the flanges 12—13 in hook 8 and against flange 10 respectively as shown in Figure 1.

Slidably mounted in, and substantially filling the housing 1, is a wooden block 16 having a bore 17 formed vertically therethrough to receive any standard, as 18, for supporting various devices not shown.

At 19 is shown a screw threaded through the outer end 6 as at 20, and slidably engaging, or passing through, a bore 21 in block 16.

By means of this construction the standard 18 may be adjusted as desired in the bore 17 and then held securely in position by tightening set screw 19. But in tightening the screw 19 on standard 18 it forces the standard against the side of the bore nearest rail 11, and consequently continued inward movement of the screw forces the entire block toward and against the rail 11, the one operation effectively binding the standard in the block 16, and at the same time clamping the housing 1 immovably on the rail 11.

In the embodiment of the invention shown in Figure 3 the screw 19 does not pass through the block 16 and communicate with the passage 17, but bears against a metallic button or disc 24 seated in the side of the block as shown.

In this embodiment the passage 17 is only slightly larger in diameter than the standard 18, and the block 16 is split clear through on one side from that side to the passage 17 as indicated at 25, and this split, is so positioned as to extend vertically of the block and at an angle, preferably at right angles, to the plane of the button 24.

By means of the construction above described

the necessary adjustments are easily made because the standard 18 has a loosely sliding fit in passage 17, and the block 16 is slidable in housing 1. But when the parts are positioned as desired and the screw 19 tightened up, the block 16 is first urged into intimate contact with the opposing side of rail 11, and then the block is caused to clamp upon the standard 18. The clamping action of the block is permitted by the resiliency of the material used, and the required pressure to obtain this clamping action may be applied to the block because the disc 24 will prevent the screw 19 from boring into the wood.

15 The above described embodiment of the invention is particularly desirable because it does not permit the screw 19 to deface the outer surface of the standard 18 as is the case when the device is constructed and used as shown in Figure 1.

In order to permit the movement of block 16 in housing 1 I provide slots as 22 and 23 in the top and bottom parts 2 and 3 respectively.

25 By loosening the screw 19 the standard 18 may be raised or lowered as desired, and at the same time the whole device may be shifted as desired along a bed rail, or removed therefrom and placed upon the opposite side of the bed or upon any other bed of similar construction.

30 Although a certain specific embodiment of the invention has been illustrated and described, it will be understood that various alterations in the details of construction and mode of assembly and operation may be made without departing from the scope of the invention as indicated in the appended claims.

I claim:

1. In combination, an angle iron rail, a hous-

ing having an opening formed therein to face the rail and an extension overlying the top of the rail terminating in a hook formed to engage the inner edge of the top of the rail and an extension overlying the bottom edge of the rail and terminating in an upstanding flange to engage the inner side of said bottom edge, a member slidably mounted in said housing to move through said opening therein and engage the rail and having a passage formed therethrough in angular relation to its direction of movement adapted to slidably engage a supporting member and a passage formed therein in angular relation to the first passage and communicating therewith, and a screw threaded 10 through said housing and passing through the second passage to engage the supporting member whereby said supporting member may be urged into fixed engagement with the slidable member and the slidable member into fixed engagement 15 with the rail.

2. A compound clamp comprising a housing provided with means disposed to engage spaced portions on one side of a supporting rail, a clamping element slidably associated therewith and disposed to engage the rail in opposed relation to said means, said element having a passage formed therethrough adapted to slidably engage a supporting standard and split on one side from the passage to its outer surface to 25 form a clamping element, and clamp operating means inserted between the housing and said element operative to simultaneously clamp the clamping element on a supporting standard therein and urge the said clamping element into 30 fixed relationship with the rail.

CLOYES R. CARSON.
